Primary Examiner — Elizabeth Albert(74) *Attorney, Agent, or Firm* — Luedeka Neely Group, PC(57) **CLAIM**

The ornamental design for a pen with seat belt cutter, as shown and described.

DESCRIPTION

FIG. 1 is a perspective view of a pen with seat belt cutter showing my new design;

FIG. 2 is a right side elevation view of FIG. 1;

FIG. 3 is a left side elevation view of FIG. 1;

FIG. 4 is a top elevation view of FIG. 1;

FIG. 5 is a bottom elevation view of FIG. 1;

FIG. 6 is a rear end view of FIG. 1;

FIG. 7 is a front end of FIG. 1; and,

FIG. 8 is an exploded view thereof.

The broken lines in the drawings are included for the purpose of illustrating unclaimed features and form no part of the claimed design.
